17 Claims. (Cl. 242—34)

1

This invention is a machine functioning to produce coreless or hollow cops of yarn for use in the textile industry. It essentially comprises a rotary spindle to which yarn is continuously supplied and on which it is, or may be, directly wound in the form of a self-sustaining tubular mass and from which such mass is stripped on completion by the retraction of the spindle, and it is provided with all necessary means whereby as each cop has been formed and discharged, and its controlling yarn severed, it is followed by another produced in the same way, and so on continuously.

Special features relate to the mechanism for mounting, moving and controlling the spindle and its associated parts so as to produce cops of uniform density and size and of any desired length and so that the end of the yarn is left easily accessible for unwinding, usually protruding from the bore of the cop. Other features will be recognized from the disclosure which follows in the drawings:

Figure 1 is a vertical section through the spindle axis of a hose-shaped cop winding machine.

Figure 2 is a side view of this hose-shaped cop winding machine.

Figure 3 is a top view hereof.

Figure 4 is a section through the gear-box on the line 4—4 in Figure 8.

Figure 5 is a section through the gear-box on the line 5—5 in Figure 8.

Figure 6 is a sectional top-view of the gear-box on the line 6—6 in Figure 4.

Figure 7 is a sectional front-view of the hose-shaped cop winding machine on the line 7—7 in Figure 1.

Figure 8 is a section on the line 8—8 in Figure 1 through the gear-box with the cover removed.

Figure 9 is a section on the line 9—9 in Figure 1 through the gear-box.

Figure 10 is a side view of the spindle-point on an enlarged scale.

Figure 11 is a side view hereof.

In a casing 1 a driving-shaft 2 is journaled and driven by any appropriate means. This shaft carries loosely thereon a compound gear comprising spur-gear 3 and worm-wheel 4. The hub of the worm-wheel is developed as a clutch member 5 fixed on the driving-shaft 2. The spur gear 3 drives through an idler 6, a larger spur gear 7, which is fast on a rotatable member 8, herein referred to as the spindle box. This box contains the winding spindle 9, which has an

angular cross-section fitting the corresponding cross-section of the bore of the box so that the spindle is rotated by the box and is longitudinally movable therein. The rear end of the spindle 9 is swivelled in a swivel head 10 by means of ball-bearings of a type which prevents separation of the spindle and the head. In the present case the spindle is shown as a square spindle.

The spindle box 8 and the swivel head 10 are built into the cover part 11 of the casing 1, and the swivel head 10 is arranged to slide in this part by means of its two lateral ribs 12 (appearing in Fig. 9), which slide in horizontal grooves 13 in the cover 11. The free end, or point 15 of the spindle, is tapered and also provided with notches 14 as shown in Figs. 10 and 11 and later referred to.

From the front of the casing there project two parallel fixed rods 16 and 18 braced to each other at their free ends by a cross-brace 17. An axially movable counter-support 19 slides on these rods parallel to the spindle. The lower part 20 embraces the rod 18. In this counter-support 19 a counter-pusher 21 is mounted in ball-bearings aligned with the spindle 9 and adapted to receive and support the free end thereof. The counter-support 19 and its pusher 21 are urged toward the spindle by a weighted cable 22, which is fastened to the support 19, and is guided over a sheave 23 on the casing and runs thence to a pulley 25 (see Fig. 7) of a weight 24. This same cable extends from the pulley 25 upwardly and over sheaves 26 and 27 for attachment to the horn 28 of the sliding-head 10 above referred to. The connection is made by clamp screws 29 (Fig. 9). Thus the weight 24 tends to urge the spindle outwardly or toward the counter-pusher, and also tends to urge the counter-pusher toward the spindle. An overweight 33, shown in Fig. 7, is attached to the cable on the counter-pusher side and biases the cable system in favor of the counter-pusher, urging it normally toward the spindle with a somewhat greater force than the spindle is urged toward the counter-pusher. Beyond this point of attachment to the slide spindle head 10, the cable 22 continues around the sheave 30 to a wind-up drum 32 on the hub of a gear 31. This is for withdrawing the spindle from the cop and will be referred to below.

When in action the spindle 9 projects from the spindle box 8 with its point supported in the counter-support 21. The yarn 34 is led to the spindle and through a thread-guide eye 36 mounted on a thread-guide finger 35, which is vibrated back and forth by means contained with-

in the casing 1, but omitted from the drawing to avoid complication. Such a thread-guide vibrating mechanism is very well known in this art. When the machine is started in operation the end of the yarn is fixed to the spindle by winding a few turns thereon, or by pulling back the counter-pusher and pinching the yarn between it and the end of the spindle. The conical pressing-roll 38, rotatably mounted on a supporting arm 39 journaled on top of the cover 11, normally bears on the conical part of the cop during the winding process and the thrust of the growing cop against this roll causes the cop and the spindle to be advanced accordingly. The driving-shaft 2 also carries a worm 40, by which it drives a compound gear 41, 43 on the control-shaft 42 which extends crosswise of the casing 1. The spur gear 43 in turn drives another gear 44, which is rotatably mounted on a cam-shaft 45. The drive of this gear-train is continuous with the drive-shaft 2.

The cam-shaft 45 receives motion from the gear 44 through a clutch mechanism now to be described and which is similar to the cam-shaft drives customarily found in machines of this general class. The purpose is to actuate the cam-shaft to the extent necessary for producing a proper sequence of operation of the other parts of the winding mechanism. The gear 44 is provided on its face with one or more drive-pins 46 (Figs. 4 and 9), a locking hook 49 carried on the adjacent disc 47, which disc is fast to the cam-shaft, is adapted to hook onto one of these pins at the appropriate intervals so that the cam-shaft will be rotated thereby. The hook is pivoted at 48 (Fig. 4), and is urged toward the pins by a spring 50. It has a trip-lug 51 adapted to encounter the nose 52 of one of the arms of a three-armed lever 53, fast on the counter-shaft 42, but only when such lever is swung to a position in the path of such lug. When such engagement occurs the effect is to disengage the hook from the drive-pin, thereby bringing the cam-shaft 45 to rest. When the trip-lug has thus encountered the nose 52 so as to stop further rotation of the cam-shaft and of itself, it remains in this position until the lever 53 is rocked in the opposite direction so as to disengage the nose from the hook. Thereupon the hook again couples with a drive-pin and resumes the drive of the cam-shaft.

In the present case less than a complete rotation is desired for the first movement of the cam-shaft and therefore another nose 54 on another arm of the three-armed lever 53 is provided. This is to be encountered by the trip-lug 51. The cam-shaft is thus caused to be rotated, under the control of lever 53, for only the arcuate distance between the two noses. It turns first about one-quarter revolution and then three-quarter revolution.

The counter-shaft 42 projects to the exterior of the casing where it carries a lever with two arms. The lower arm 55 is connected by a link 56 to a lever 57 mounted on a front casing-bracket 58 and in turn connected to a pull-link 59, the front end of which is guided in a hole in the cross-brace 17 and carries a collar 60 in a position in the path of movement of the counter-support 19. As the effect of the elongating cop 37 pushes the counter-support against the collar 60, the resulting pull on the link 59 and the parts just referred to, rocks the shaft 42 and thereby rocks the three-armed lever 53, above described, in the direction to release the nose 52.

from the drive-hook 49 and thus produce a partial rotation of the cam-shaft 45.

The upper arm 61 of the two-armed lever 55, 61 on the shaft 42 engages with one arm 62 of a horizontal lever 62—63, which is connected by a connecting-rod 64 to an abutment member 66 mounted to slide in the slot 65 of the cover structure. The abutment 66 is put in the path of the sliding head 10 by the operation of the connections just mentioned. When the sliding head hits it, the effect is to rock the shaft 42 in the opposite direction to that imparted to it by the collar 60, and thereby the three-armed lever 53 and the collar 60 are restored to their former positions.

The several functions of this machine are performed in their proper sequence by a series of cams on the cam-shaft 45, described as follows:

The compound gear 3—4 is shifted back and forth on the drive-shaft 2 so as to be alternately connected to the clutch 5 on said shaft and a brake-socket at its other end, by means of a shipper lever 68—69. This lever is pivoted between lugs 70 and 71 inwardly projecting within the casing. It is connected by a link 72 (Fig. 5) to the cam lever 73—74 appurtenant to the disc cam 75 carried by the cam-shaft 45. It is held up to the cam by a spring 76.

An adjacent cam 77, through its cam lever 78 and link 79 operates a cable-clamp 80 (Fig. 5) against the pressure of a spring 82, which thrusts against collar 83 on the link 79. The cable-clamp comprises a bolt 80 with a wide head 81. The cable 22 runs through a hole in this bolt back of the head and when the bolt is actuated by the spring it clamps the head against the cable so that it cannot be moved by the effect of the weight. This part of the cable runs to the counter-support 19, and accordingly, when the cable is locked, this counter-support remains stationary on its guideway rods. This occurs when the spindle is being retracted for stripping off the cop.

The next cam 84 on shaft 45 and its cam lever 85 are connected by link 86 to a push-rod 87 to operate the yarn cutting mechanism against the pressure of a spring 88 on the rod thrusting against a collar 89 thereon. The cutting mechanism comprises a lower blade 90 fast to the push-rod 87, an upper blade 91 riding on the lower one and held to it by screws, and slots as indicated in Fig. 6. The blades are respectively provided with flared seizing-beaks extended from their cutting edges 92 and located just below the spindle box 8.

The outer end of the upper blade over-lies a flat cam plate 95 fixed to the side of the casing and engaging a cam slot in such plate by means of its cam stud 93. From the shape of the cam slot it will be observed that the two blades move bodily forward, during the initial advance of the push-rod 87 and then move relatively to each other to make the shearing stroke in the last part of the rod movement. Thus the yarn is caught and brought into the action of the shearing edges. The lower blade 90 is also guided on the cam plate 95 by means of its lug 96 engaging the under surface thereof.

Still another cam is provided on cam-shaft 45. This is for controlling the cable system and is constituted of a projection 99 (Fig. 9) formed on the face of disc 47 which carries the locking hook 49, above referred to. This face cam 99 actuates a shipper lever 97 pivoted on or between the above mentioned lugs 70 and 71 and carrying a roller 101 as shown.

copies an annular groove 102 of a compound gear and clutch member 101—104 freely journaled on arbor 103. This compound member is for driving the wind-up gear 31, above mentioned, and which is journaled in the cover part of the casing so that it meshes with gear 107 when the cover is in place. Such drive is not effected, however, until the shipper lever 97 shifts the clutch member 104 into engagement with its complementary clutch member 105, thereby connecting it to the worm-wheel 106, constantly driven by its engagement with the worm 40 on drive-shaft 2. The drive thus imparted to the wind-up gear pulls the cable 22 in the direction to pull the winding spindle inwards of the spindle box 8, thus stripping off the cop, which has been wound on it. The wind-up gear pulls the swivel head 10 of the spindle rearwardly until it engages and moves to right the abutment 66. As already explained, this rocks the shaft 42 and the three-armed lever thereon to the right.

As shown in Fig. 6, the three-armed lever 53 carries a cam projection 109 on its side face, which, when thus moved by the rocking of shaft 42, engages the cam surface 108 on the shipper lever 97, causing it to open the clutch members 101—105, thus terminating the wind-up period. When the spindle is thus withdrawn into the spindle box, the cop which has been wound thereon is stripped off. It will be observed that this winding up of the cable has occurred against the pull of the weight 24, the tendency of which is to restore the spindle to its advanced position. Means are provided to prevent immediate advance of the spindle in the form of a pawl 110 journaled on shaft 42, and normally engaging the teeth of the gear 107 to prevent its reverse rotation. This pawl, as shown in Fig. 4, has a weighted end 111 which rides on the edge of a disc cam 112 on cam-shaft 45. It is actuated by this cam to release the wind-up mechanism when the spindle is to be next advanced.

The conical presser-roll 38 is held in its working position, indicated in Fig. 3, by its supporting lever 39—113, the arm 113 of which is engaged to a bell-crank lever 115, which latter bears, by its cam-roller 116, upon the disc cam 117, also borne by the cam-shaft 45, on its external extremity. The function of this cam is to swing the presser-roll clear of the wound cop when it is time for the latter to be stripped from the spindle. This allows the cop to abut the end of the spindle box for stripping purposes.

Still another cam 119, mounted on the other projecting end of cam-shaft 45, engages the cam-bowl 120 of lever 121—122, the forward end of which engages the arm 123 of a pivoted cradle 124 placed just below the spindle in a position to catch the cop which is stripped from the latter. The forward end of this cradle finds a support in the cross-brace 11, above referred to and as shown in Fig. 3. The cradle holds the cop only long enough for its trailing yarn to be severed by the knife mechanism, whereupon it rocks on its support when the lever arm 122 is lowered, and thus discharges the cop from the machine.

During the normal course of winding, the clutch 4—5 being closed, the yarn 34 is wound up on the spindle 9 under the guidance of the vibrating thread-guide 35. In the same proportion as the cop 37 increases in length, it is pushed forward by reaction against the presser-roll 38, carrying the spindle with it, also the sliding-head 10, and also pushing ahead of it the counter-pusher 21 and the support 19. At such time the

clutch 104—105 is open and the retaining pawl 110 is clear of the gear 107, so that the cable is free to unwind from the wind-up drum. The locking hook 49 is resting on the nose 52 of the three-armed lever 53 by its trip-lug 51 and is thereby held away from the driving pins 48. The cam-shaft is therefore still. The weight 24 always urges the counter-pusher 21 against the point 14 of the spindle 9 under pressure, while the overweight 33 tends to move both in a backward direction and presses the cop against the presser-roll 38. This pressure, which influences the compactness of the cop can be regulated by adjusting the size of the overweight 33.

When the cop has been wound to its desired length the counter-support 19 strikes and moves to the left the stop-collar 60, thereby rocking the shaft 42, as already explained, in the direction to remove the nose 52 from the hook 49 and to advance the other nose 54 into the path of the hook, about 90° distant. Thereby the locking-hook 49 falls into connection with one of the drive-pins 46, thus coupling the cam-shaft to the revolving gear 44. The cams on the cam-shaft call up the following actions, all in the proper sequence:

1. Cam 75 opens clutch 4—5, thus stopping the rotation of the spindle, also of the thread-guide action.
2. Cam 117 swings the presser-roll 38 away from the cop.
3. Cam disc 11 releases the cable clamp 80, causing it to clamp cable 22, thus retaining the counter-support 19 in its most forward position.
4. Cam 119 rocks the receiving cradle into horizontal or receiving position.
5. Cam 99, through shipper lever 97—98 and its spring 100, closes clutch 104—105. Thereby the wind-up wheel 31 is set into rotation and winds up the cable on the drum 32, pulling the spindle backwards and into the spindle box, while the counter-pusher 21 remains, for the time being, in its extreme forward position.
6. Cam 112 releases the pawl 110 so that it is free to engage the teeth of wind-up gear 107.
7. The trip-lug 51 of locking-hook 49, after about one-quarter of a rotation of cam-shaft 45, comes into contact with the nose 54 of the three-armed lever 53 and is thereby disengaged from its drive-pin and the cam-shaft 45 comes to rest. In the meantime the clutch 104—105 being closed, the cable continues to be wound-up on the drum 32 until the swivel slide-head 10 of the spindle 9 encounters the abutment 66 and through the linkage already described, rocks the shaft 42 and the three-armed lever thereon in the other direction. This has the effect, first of opening clutch 104—105 to stop the retraction of the spindle; next, the nose 54 releases locking-hook 49, allowing the cam-shaft to continue and complete its rotation, that is, until the hook again encounters the nose 52. Pawl 110, which had already been set free prevented the unwinding of the wind-up wheel when the clutch 104—105 was disengaged, so that the spindle 9 remains, for the time being, in its withdrawn position.
8. The said cam 99 then engages the lower end of shipper lever 97 to further separate the clutch members 104—105 and hold them well out of contact until they are next called into use.
9. Cam 117 restores the presser-roll 38 to its working position.
10. Cam 77 opens the cable clamp, thereby allowing the counter-support 19 and pusher 21 to

return to their starting point, thereby engaging the pusher with the point of the spindle.

11. Cam 84 advances the cutting mechanism a partial stroke until the yarn, which then extends from the thread-guide eye to the bobbin in the cradle, is caught or located between the cutting edges 92.

12. Cam 112 then frees pawl 110 from the gear 107, thereby allowing the cable to unwind under the pull of the weight, thus advancing the spindle to meet the rotary pusher 21. In such forward movement the notches 14 in the spindle-point 15 catch hold of the yarn extending down from the guide-eye and pinch it tightly against the pusher, thus fixing it to the spindle for the start of the next cop.

13. Cam 84 then continues to move the cutting mechanism forwardly until, by the motion of the upper blade, produced by the cam groove 94, the cutting edges are closed and the yarn severed.

14. Cam 119, operating by levers 122 and 123, then rocks the receiving cradle 124 to dump the cop into a trough or place of deposit.

15. Cam 75 closes the clutch 4—5 just prior to the arrival of the hook 49 against the nose 52 of lever 53, which stops the cam-shaft, and thereupon the same cycle is repeated.

It may be noted that when the spindle withdraws from the counter-pusher 21, it leaves the originally pinched end of the yarn protruding from the end of the cop as a loop, indicated at 34', and therefore easily accessible for the later unwinding of the cop.

I claim:

1. In an automatic machine for winding hollow cops, a winding spindle, a thread-guide coacting therewith to guide the yarn back and forth with relation to the spindle, a rotary spindle box in which the spindle slides and by which it is rotated, a counter-pusher movable in alignment with the spindle and adapted to engage the point thereof, means normally urging the pusher toward the spindle and the spindle toward the pusher, means for introducing the yarn between the spindle and the pusher, means for advancing the spindle at a rate conforming to the elongating cop and separate means for retracting the spindle for stripping the cop, in combination with automatic mechanism for causing the movements of said parts according to a predetermined recurring sequence.

2. The combination of claim 1 in which said means for advancing the spindle is the elongating cop itself, including a relatively fixed abutment against which it thrusts.

3. The combination of claim 1 in which said means for advancing the spindle is the elongating cop itself and a presser-roll against which the cop thrusts and in which means are provided for removing said presser-roll in advance of stripping.

4. The combination of claim 1 in which the means for urging the spindle point and counter-pusher towards each other is biased in favor of the counter-pusher.

5. The combination of claim 1 in which means are provided to lock the counter-pusher against movement when the spindle is being retracted.

6. The combination of claim 1 in which the means for urging the spindle and counter-pusher together is a cable system connected respectively to these parts and movable on sheaves to accommodate the spindle advance.

7. The combination of claim 1 in which the

spindle point is notched to catch the yarn and clamp it to the counter-pusher.

8. In an automatic, hollow cop, winding machine the combination of a longitudinally movable winding spindle, a counter-support for the point of the spindle, means for advancing the spindle into engagement with said counter-support, and means for holding yarn extending from a discharged cop in the path of the advancing spindle, to be clamped thereby against the counter-support.

9. In an automatic, hollow cop, winding machine, a longitudinally movable winding spindle, means for advancing it by the effect of the elongating cop, a counter-pusher maintained in supporting contact with the point of the spindle, and means for withdrawing the spindle from said counter-pusher when stripping the cop from the spindle.

10. The combination of claim 9 in which a cable system serves to maintain the counter-pusher in supporting contact with the spindle, said system comprising a cable swivelly connected to the spindle and also connected to the pusher, and means applied to said cable for imparting the force thereto which maintains said pusher and spindle in contact.

11. The combination of claim 9 in which the means for maintaining the pusher and spindle in contact is a cable system one end of which is swivelled to the spindle and the other end of which is connected to the pusher, with means applied to the cable to put tension thereon to maintain the contact, and an overweighting means also applied to the cable to bias said system in favor of the pusher.

12. In an automatic, hollow cop, winding machine, a longitudinally movable winding spindle, means for advancing it by the effect of the elongating cop, a counter-pusher, a cable connected to the spindle and to said counter-pusher to maintain the counter-pusher in supporting contact with the point of the spindle, and means for withdrawing the spindle from said counter-pusher when stripping the cop from the spindle.

13. The subject matter of claim 1 characterized by the fact that the means for urging the spindle towards the counter-pusher includes a swivel head in which the spindle can rotate.

14. In an automatic, hollow cop, winding machine, a longitudinally movable winding spindle, means for advancing it by the effect of the elongating cop, a counter-pusher, a cable connected to the spindle and to said counter-pusher to maintain the counter-pusher in supporting contact with the point of the spindle, a weight suspended by said cable causing said cable to urge the counter-pusher and spindle into contact with each other, a member against which the cop thrusts as it grows, an overweight attached to the cable pressing the cop against the said member, and means for withdrawing the spindle from said counter-pusher when stripping the cop from the spindle.

15. In an automatic, hollow cop, winding machine, a longitudinally movable winding spindle, means for advancing it by the effect of the elongating cop, a counter-pusher maintained in supporting contact with the point of the spindle, a member against which the winding end of the cop presses as it is wound, means to move said member out of contact with the cop before withdrawing the spindle from the cop, means for withdrawing the spindle from said counter-pusher when stripping the cop from the spin-

die, and means to be engaged by the end of the cop as the spindle is withdrawn to strip the cop from the spindle.

16. The subject matter of claim 1, characterized by the fact that the said automatic mechanism comprises a cam shaft, a stop operable by the counter-pusher on the completion of a cop to start said cam shaft, means to stop the cam shaft after spindle retraction has begun, and a stop operable by the spindle mechanism at the end of its retraction to restart the cam shaft.

17. In an automatic, hollow cop, winding ma-

chine, a longitudinally movable winding spindle, means for advancing it by the effect of the elongating cop, a counter-pusher, a cable connected to the spindle and to said counter-pusher to maintain the counter-pusher in supporting contact with the point of the spindle, means for relieving the counter-pusher of the pull of the weighted cable, and means for withdrawing the spindle from said counter-pusher when stripping the cop from the spindle.

die, and means to be engaged by the end of the cop as the spindle is withdrawn to strip the cop from the spindle.

16. The subject matter of claim 1, characterized by the fact that the said automatic mechanism comprises a cam shaft, a stop operable by the counter-pusher on the completion of a cop to start said cam shaft, means to stop the cam shaft after spindle retraction has begun, and a stop operable by the spindle mechanism at the end of its retraction to restart the cam shaft.

17. In an automatic, hollow cop, winding ma-

chine, a longitudinally movable winding spindle, means for advancing it by the effect of the elongating cop, a counter-pusher, a cable connected to the spindle and to said counter-pusher to maintain the counter-pusher in supporting contact with the point of the spindle, means for relieving the counter-pusher of the pull of the weighted cable, and means for withdrawing the spindle from said counter-pusher when stripping the cop from the spindle.
